(57) **CLAIM**

The ornamental design for an adjustable accessory attachment, as shown and described.

DESCRIPTION

FIG. 1 is a top perspective view of the adjustable accessory attachment with a grip member in an extended position; FIG. 2 is a bottom perspective view thereof; FIG. 3 is a left side view thereof, a right side view being a mirror image of the left side view; FIG. 4 is a first end view thereof; FIG. 5 is a second end view thereof; FIG. 6 is a top view thereof; FIG. 7 is a bottom view thereof; FIG. 8 is another top perspective view thereof with the grip member retracted; and, FIG. 9 is another top perspective view thereof with the grip member removed. The evenly spaced broken lines depict portions of the claim that form no part of the claimed design. The dash-dot-dash broken lines represent the bounds of the claim and form no part thereof.

1 Claim, 9 Drawing Sheets
